UNITED STATES PATENT OFFICE.

PAULIN A. LACOUR, OF PINEVILLE, LOUISIANA.

CAR-DOOR.

1,158,510.

Specification of Letters Patent.

Patented Nov. 2, 1915.

Application filed July 31, 1915. Serial No. 42,929.

To all whom it may concern:

Be it known that I, PAULIN A. LACOUR, a citizen of the United States, residing at Pineville, in the parish of Rapides and State of Louisiana, have invented certain new and useful Improvements in Car-Doors, of which the following is a specification, reference being had to the accompanying drawings.

This invention relates to certain improvements in car doors, and it is an object of the invention to provide novel and improved mechanism coacting with the door whereby it may be readily and conveniently adjusted relative to the car opening so that the door may be effectively maintained in closed position, or positioned in such a manner as to be conveniently adjusted into open position.

The invention consists in the details of construction and in the combination and arrangement of the several parts of my improved car door whereby certain important advantages are attained and the device is rendered simpler, less expensive and otherwise more convenient and advantageous for use, all as will be hereinafter more fully set forth.

The novel features of the invention will be carefully defined in the appended claim.

In order that my invention may be the better understood, I will now proceed to describe the same with reference to the accompanying drawings, wherein—

Figure 1 is a view in elevation illustrating a car door constructed in accordance with an embodiment of my invention; Fig. 2 is a fragmentary view in bottom plan of the device as disclosed in Fig. 1; Fig. 3 is a sectional view taken substantially on the line 3—3 of Fig. 1; Fig. 4 is a view similar to Fig. 3, but showing the door adjusted into an inoperative position relative to the door opening; Fig. 5 is a sectional view taken substantially on the line 5—5 of Fig. 1; and Fig. 6 is a sectional view taken substantially on the line 6—6 of Fig. 1.

As disclosed in the accompanying drawings, 1 denotes a side wall of a car body provided with the opening 2 with which the door 3 is adapted to coact, said door 3 being suspended from the track-way 4 whereby said door is capable of movement longitudinally of the wall and may be readily and conveniently swung laterally with relation to the wall 1.

Secured to the outer face of the door 3 are the straps 5 and 6 depending below the

door and terminating in the vertically disposed loops 7 through which extends the crank portion 8 of the operating member 9, said crank portion 8 being of a length substantially equal to the length of the track-way 4 so that the door 3 may be readily adjusted into open position longitudinally of the wall 1. The strap 6 has its lower portion offset laterally and in a direction longitudinally of the wall 1 so that it may avoid the adjacent supporting sill S and the crank portion 8 is provided with the offset 10 so that said sill offers no obstruction to the rotation of the operating member 9.

The operating member, as herein embodied, comprises an elongated member of requisite gage having one extremity angularly disposed to afford the lever 11 whereby the requisite axial rotation may be imparted to the member 9 in order that the crank portion 8 may coact with the straps 6 and 7 in such a manner as to swing the door outwardly so that the same may be moved upon the track-way 4 for adjusting the door into an open position or for swinging the door inwardly so that the same will be properly disposed relative to the opening 2.

The wall 1 has projecting outwardly therefrom adjacent a vertical edge the stop lug 12 to limit the movement of the door in one direction upon the track-way 4 so that said door will be properly positioned relative to the opening 2 and the inner face of the door is provided with a second lug 14 positioned adjacent the vertical margin thereof remote from the lug 12, said lug 14 being adapted to engage with a vertical edge of the opening 2 so as to maintain the door against displacement when in closed position especially as a result of undue jar. The operating member 9 as herein embodied is rotatably supported by the bearings 15 depending from the side wall 1 and also depending from said side wall is the hook member 16 with which the crank portion 8 is adapted to engage when the door is in closed adjustment, the coaction between the portion 8 and the hook member 16 serving to hold the operating member 9 against accidental rotary movement. It is also to be understood that the lever 11 is provided with a perforation 17 through which a suitable seal is adapted to be directed, said seal coacting with a suitable staple 18 or other member secured to the outer face of the wall 1.

From the foregoing description, it is thought to be obvious that a car door constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

In combination with a wall provided with an opening, a door for said wall mounted for movement longitudinally of the wall and capable of swinging movement laterally with relation to the wall, a strap depending from the door and terminating in an elongated loop, and an operating member supported by the wall and disposed through the

loop of the strap, the portion of the operating member within the strap being offset whereby the door is swung laterally upon axial rotation being imparted to the operating member, said offset portion of the operating member being of such a length as to afford no obstruction to the movement of the door longitudinally of the wall, a laterally disposed operating lever carried by the operating member and having its free extremity provided with an eye, an attaching member carried by the wall and adapted to coact with the eye of the lever, and a hook member depending from the wall and coacting with the offset portion of the operating member to hold said operating member against accidental rotary movement when the door is in closed position relative to the opening.

In testimony whereof I hereunto affix my signature in the presence of two witnesses.

PAULIN A. LACOUR.

Witnesses:

M. T. HASLER,
S. R. LEE.
